[57] CLAIM

The ornamental design for a key ring splitter, as shown and described.

DESCRIPTION

FIG. 1 is a perspective view of a key ring splitter showing our new design;

FIG. 2 is a top plan view, the bottom plan view being a mirror image thereof;

FIG. 3 is an end elevational view, the views from the left and the right end being identical; and,

FIG. 4 is a side elevational view, the views from the left and the right side being identical.

FIG.1

FIG.2

FIG.3

FIG.4
